PERMUTATION LOCK

George D. Dillon, Denver, Colo.

Application September 30, 1938, Serial No. 232,501

5 Claims. (Cl. 70—333)

This invention relates to improvements in permutation locks and relates more particularly to an attachment that can be applied to such locks to prevent them from being opened by a removal of the tumblers.

It often happens that safes in small stores, banks and other places are opened by burglars and the cash or other valuables taken. The ordinary cheap safes are almost without exception provided with combination or permutation locks of the type in which a plurality of circular disks or tumblers are positioned in a box on the inside of the door and manipulated by a knob that is located on the outside of the door. Each tumbler has a notch in its periphery and a gravity dog rests on the peripheries of the tumblers and normally holds the bolts in projected or locking position. When the tumblers have been adjusted so as to bring the notches in line underneath the gravity dog, the latter will drop and release the bolts which can then be withdrawn.

Most burglars, whatever method they use, first break the outside knob from the safe so as to furnish access to the interior of the lock box. After the knob has been removed the tumblers are then driven inwardly by means of a punch and sledge, or by means of an explosive. The idea being to remove the tumblers so that the gravity dog will drop and release the bolts, which can then be withdrawn in the usual way.

It is the object of this invention to provide means, within the lock box, for automatically engaging the gravity dog and latching it in bolt engaging position, whenever the tumblers are subjected to abnormal movement or to severe shocks, as when the knob is being forcibly broken away.

In order to describe the invention so that it can be readily understood, reference will now be had to the accompanying drawing in which it has been illustrated and in which

Figure 1 is a side elevation of a combination lock, showing the tumblers and the safety attachment in place, the gravity dog having been omitted for the sake of clearness.

Figure 2 is an end elevation, looking in the direction of arrow 2 in Fig. 1, the gravity dog being shown in position.

Figure 3 is a section taken on line 3—3, Fig. 2 and shows the latch that holds the safety device inoperative.

Figure 4 is a section taken on line 4—4, Fig. 1 and shows the dog engaging member, and

Figure 5 shows a proposed modification.

In the drawing numeral 6 designates the door of the safe and 7 the lock box which is attached

to the inside of the door. Numerals 8 designate the tumblers and 9 the knob that is positioned on the outside of the door and which is operatively connected with the tumblers by means of a shaft 10. The construction of the lock has not been shown because it is old and well known. The tumbler farthest to the left in Fig. 1 is attached directly to shaft 10 and serves to set the other tumblers which become temporarily interconnected when pins 11 come into engagement. Each tumbler is provided with one peripheral notch 12 and when these are brought into alignment directly below the elongated pawl 13 of the gravity dog 14 the pawl drops into the notches and its movement about the pivot 15 releases the bolts which can then be withdrawn.

It is evident that if the tumblers are removed from beneath the pawl 13 the dog can turn and release the lock. If after the knob has been broken off a punch is applied to the outer end of the shaft 10 and the latter is driven inwardly carrying with it the tumblers so that they are removed, the gravity dog is free to turn and release the bolt.

It is evident from the above that as long as the gravity dog remains in the position shown in Fig. 2 the lock cannot be opened even if the tumblers are removed.

For the purpose of automatically moving a support into place under the projection 16 of dog 14, whenever the tumblers are subjected to a force which moves them inwardly the following mechanism has been provided.

A square bar 17 is provided at each end with an attaching member comprising a rectangular portion 18 from diagonal corners of which projections 19 extend. The projections are perforated for the reception of screws 20 by means of which the assembly is attached to a corner of the lock box 7 in the manner shown in Fig. 2. Slidably mounted on the bar, between the two end supports are two square rings 21 and 22. The one to the right in Fig. 1 is provided with a set screw 23 by means of which it can be clamped in any suitable position. Member 21 is provided on one side with an integral arm 24 having a narrow flange along its lower edge. A compression spring 25 surrounds the bar 17 between parts 18 and 21 and tends to move member 21 towards member 22 that serves as a stop. The end support 18 at the left in Fig. 1 is provided at its inner corner with two lugs or ears 26 between which is pivoted a bell crank lever having arms 27 and 28. It will be observed that the slidable loop 21 is provided with a lug 29 and that the end of arm 28

has a hook 30 that engages lug 29 and latches member 21 against movement in response to the action of spring 25. Attached to arm 27 is an extension 31 which has a slot 32 for the reception of the clamping bolt 33. The outer end of the extension 31 has a head 34 that rests against the outer surface of the innermost tumbler or disk 8. Stop 22 is so positioned that when member 21 is released and moved against this stop by the action of the spring, the end of the slidable extension 35 of arm 24 will be positioned underneath lug 16 of the gravity dog 14 and support the latter so that it will not move downwardly if the tumblers 8 are removed. In order to prevent member 21 from being moved away from the stop 22 after it has been released, a hook 36 may be pivotally attached to member 22 and so proportioned that it will engage arm 24 and latch the parts in the position shown in Fig. 5. A lug 37 serves to limit the downward movement of hook 36 and a spring 38 holds the hook normally in engagement with lug 37.

Let us now assume that the parts are in the position shown in Fig. 1 and that an attempt is made to open the safe. The burglar, by means of a chisel and sledge, removes the knob 9, as by breaking shaft 10. He then begins to drive shaft 10 inwardly by means of a punch and sledge and since the innermost disk 8 is attached to the shaft 10 it will be moved inwardly. The inward movement of disk 8 turns the bell crank lever about its pivot and disengages hook 30 from lug 29 and thereby releases slide 21, which is immediately moved towards stop 22 by the action of the spring 25. This movement of slide 21 brings the end of arm 35 underneath lug 16 in the manner indicated in Fig. 2 and supports the gravity dog in such a way that it will not move to unlocking position even after all of the disks 8 have been removed. The burglar then finds that the lock will not open and unless he is familiar with the construction of the safety catch and provided with special tools, he will be unable to open the lock after having removed the tumblers.

The attachment is of simple construction and can be readily applied to any lock or may be supplied as standard equipment when the lock is manufactured. By making arms 24 and 27 in two parts the device can be adjusted to fit all sizes of locks.

In the drawing bar 17 has been shown as square but it may have any other non-circular cross section and may also be round, but in the latter case the slidable ring 21 must have a splined connection that prevents it from rotating on the shaft.

If the gravity dog is not provided with a lug 16 such a lug may be welded thereto when the safety attachment is installed.

Having thus described the invention, what is claimed as new is:

1. In a permutation lock having a plurality of spaced parallel tumblers mounted for coaxial rotation, each tumbler having a peripheral notch, and a gravity dog having a pawl portion, supported on the peripheries of the tumblers, means for engaging and supporting the dog independently of the tumblers comprising a guide, a slide movable thereon, means comprising a spring for urging the slide in one direction, a latch for holding the slide from movement, a supporting arm carried by the slide for engaging the dog and supporting it when the slide is in a predetermined position and means operated by an abnor-

mal movement of the tumbler for releasing the latch, thereby permitting the slide to move in response to the action of the spring and bring the supporting arm into dog engaging position.

2. In a permutation lock having a plurality of spaced parallel tumblers mounted for coaxial rotation, each tumbler having a peripheral notch, and a gravity dog having a pawl portion, supported on the peripheries of the tumbler, means for engaging and supporting the dog independently of the tumblers comprising a guide, a slide movable thereon, means comprising a spring for urging the slide in one direction, a latch for holding the slide from movement, a supporting arm carried by the slide for engaging the dog and supporting it when the slide is in a predetermined position, a stop adjustably attached to the guide, and means operated by an abnormal movement of the tumblers for releasing the latch, thereby permitting the slide to move in response to the action of the spring and bring the supporting arm into dog engaging position.

3. A safety device for use in a permutation lock having a plurality of axially aligned rotatable tumblers having each a peripheral notch, and a lock releasing gravity dog normally held in operative position by the tumblers, means for engaging and holding the dog in operative position independently of the tumblers comprising a guide, means for holding the guide in a predetermined position relative to the tumblers and dog, a slide non-rotatably but longitudinally movable on the guide, an arm projecting from the slide, positioned to engage and support the gravity dog when the slide is in a predetermined position, means comprising a spring for urging the slide to dog engaging position, a stop on the guide for limiting the movement of the slide in response to the action of the spring, a latch for holding the slide in opposition to the action of the spring, and means operated by the movement of a tumbler in the direction of its axis of rotation for releasing the latch.

4. A permutation lock comprising in combination, a plurality of longitudinally spaced coaxial tumblers having each a peripheral notch, a bolt latching gravity dog having a pawl positioned for movement into the notches when they are positioned in alignment, a dog supporting arm, mounted for movement to and from dog engaging position, resilient means for urging the arm into engagement with the dog to stop its movement towards bolt releasing position, a latch for holding the arm against the action of the spring, and means responsive to an abnormal movement of the tumblers for releasing the latch whereby the arm may move to operative position.

5. A safety attachment for use in a permutation lock having a plurality of tumblers and, a bolt latching dog held in operative position by the tumblers, comprising in combination, two spaced brackets, a noncircular guide having one bracket attached to each end, a slide carried on the guide, a pawl engaging arm extending laterally from the guide, a spring encircling the guide between one bracket and the slide, a trigger pivoted to the bracket which serves as an abutment for the spring, the slide and the trigger having cooperating latching means for holding the slide in a predetermined position in opposition to the action of the spring, and an angular extension of the trigger for engagement with the tumblers of a permutation lock.
